UNITED STATES PATENT OFFICE.

THOMAS E. CLARK AND JAMES E. CLARK, OF DETROIT, MICHIGAN, ASSIGNEES TO CONTINUOUS TRAIN CONTROL CORPORATION, OF DETROIT, MICHIGAN, A CORPORATION OF MICHIGAN.

TRAIN-CONTROL SYSTEM.

Application filed May 20, 1925. Serial No. 31,633.

This invention relates to means for controlling the operation of railway trains by means of high-frequency currents of different wave lengths propagated in each of the several blocks of the track by means of transmitting mechanism connected to the exit end of the block, the transmitting mechanism of each block being controlled as to wave lengths by the transmitting mechanism of the block in advance, and the transmission mechanism of each block being inoperative unless the block of track to which it is connected is occupied; and the object of this invention is to provide a transmitting mechanism of this character, and control devices therefor, which will propagate current of one predetermined wave length in the rails of its block when the two blocks in advance are unoccupied, and will propagate current of another wave length when either of the two blocks in advance is occupied, and also when the transmitting mechanism of the block in advance is out of order.

A further object of this invention is to provide instrumentalities on the locomotives and other vehicles equipped with air brakes, embodying collector coils adapted to pick up induced current from adjacent the rails, thermal-junctions for translating the high-frequency induced current into direct current capable of affecting a polar relay, and two visible signal lamps to indicate the character of the current in the track.

These objects are attained by means of the present invention which consists of a vacuum tube, proper circuits connecting it to a current source and to the track rails, relays to select proper circuits so that the current created by the vacuum tube will be of one or another predetermined wave length, and means responsive to the presence of a vehicle in the first or second track block in advance, and in the block to which the vacuum tube is connected for controlling the operation of the relays.

It further consists of instrumentalities including collector coils on a locomotive or other vehicle, adapted to pick up high-frequency current from adjacent the track rails and tuned to the wave lengths of the several currents propagated therein, a pair of signals, a polar relay for closing circuits to these signals according as one or the other collector coil picks up current, and circuits

between this relay and the instrumentalities for picking up the current.

It also consists in a stick relay connected into the circuits on the vehicle and controlling the operation of a valve in the air line of the vehicle, this relay being deenergized when the current picked up by the collector coils is of one wave length.

It also consists of the details of construction illustrated in the accompanying drawings and particularly pointed out in the claims.

In the drawings, Fig. 1 is a diagram illustrating three track signal installations combined with control installations in different positions, together with a vehicle equipment adapted to co-operate therewith. Fig. 2 is a diagram of a current transformer and transmitter adapted for use with the track installations shown in Fig. 1. Fig. 3 is a diagram of the locomotive equipment.

Similar reference characters refer to like parts throughout the several views.

The mechanism and circuits shown in the drawings are of the same general character as those shown in co-pending application of Thomas E. Clark, Ser. No. 23,514, filed April 16, 1925, and again employ the general circuits of a three-position approach-light signal system including the signal batteries which are made use of to energize the train control units. The electro-pneumatic valve on the locomotive and a portion of the circuits leading thereto are also employed. The circuits which belong to the signal system are indicated by lighter lines than those which belong to the train control installations, and the blocks of track and the signal and control stations therefor are again indicated by the letters A to D inclusive. The green, yellow and red lamps of the signal stations again indicate "clear", "caution" and "danger", that is, that at least two blocks in advance are unoccupied or that the second block in advance is occupied, or that the next block in advance is occupied, respectively. Each signal installation and each train control installation is governed by the station next in advance, and none of these installations function unless the tracks of the block to which it is attached is occupied.

Referring now to Fig. 1, the rails 1 and 2 are those where the traffic is always in one direction, that is, from right to left. The

blocks B and D are supposed to be occupied and two blocks in advance of block B unoccupied. A green signal light should therefore show at station B, a red light at station 5 C and a yellow light at station D. The rails are divided into blocks by the insulating joints 3, and a single indicator 4 comprising three lamps is positioned at the entrance end of each block. A track relay 7 is connected 10 to each block at its exit end by means of wires 5 and 6, and is energized by the track battery 8 which connects to the entrance end of the block by means of wires 9 and 10, a resistance 11 preventing damage to the battery 15 when the rails are short-circuited by means of a vehicle on the track.

The circuits to the lamps are controlled by the polar neutral relay 14 which is connected to the station ahead by the wires 15 and 16. 20 When positive current passes over the wire 15, the relay becomes energized and its armatures 14^a and 14^c swing clockwise. They swing counter-clockwise when negative current passes to the relay over wire 15, and remain in their last position when no current passes over this wire which occurs when the block in advance is occupied; that is, when the track relay 7 of the station in advance is deenergized. In the present case, positive 25 current is received by relay 14^b, but just before the train left block C, relay 14^c was receiving positive current over wire 15, so that its armatures *e* and *f* are in clockwise position.

30 In station B, current from the battery 13 flows to the lamp stand 4 over wire 17 and from the green lamp G back to the battery over wire 18, armature 14^a, wire 19, armature 14^a, wire 20, armature 7^a, and wire 21, the armature 7^a being in dropped position which always occurs when the block to which it is connected is occupied. If no current were flowing to the relay 14 over the wire 15, current would flow to the lamp stand from 35 the battery and from red lamp R over wire 23, armature 14^a, wire 20, armature 7^a and wire 21 to the battery. When negative current flows to relay 14 over wire 15, current flows from the battery over wire 17 to the yellow lamp Y, then over wire 24, armature 14^e, wire 19, armature 14^d, wire 20, armature 7^a, and wire 21 to the battery. It will be noticed that these circuits are never closed when relay 7 is energized, and that wire 15 40 connects to the battery, from which it receives current, through the armature 7^b which drops whenever the block is occupied.

A high-frequency current of one of two wave lengths is propagated in the rails of 45 each occupied track section or block, one wave length whenever the next or second block in advance is occupied, and the other whenever at least two blocks in advance are unoccupied. In station B, positive current 50 is coming in to relay 14 over wire 15. Cur-

rent therefore flows from battery 13 over wires 26 and 27 to the transformer 28 and thence over wires 29 and 20, armature 7^a and wire 21 back to the battery.

This transformer connects to the rail 1 by 55 means of the wire 30, relay 31, and wires 32 and 5, and to the rail 2 by means of the wire 33, condenser 34, and wires 35 and 6. It is shown diagrammatically in detail in Fig. 2. The wires 27 and 29 terminate in a motor- 75 generator 36 and in the filament 37 of a vacuum tube 38, an adjustable resistance 39 in the filament circuit being provided to control temperature. The wire 27 also carries high-voltage current from the motor-generator to 80 the grid coil 40 to which it connects by means of wire 41 and the other end of this coil connects to the grid 42 by way of the condenser 43 and grid leak 44.

The circuit to the plate 45 consists of the 85 wire 46, coil 47, and wires 48 and 49, and this coil is shunted by the variable condenser 50 whereby the oscillations may be limited to a predetermined wave length, and these 90 oscillations are transmitted to the wires 30 and 33 before described through the output coil 52, this output being materially increased upon the near approach of a vehicle whose axle short circuits the track; such increase 95 builds up a strong magnetic flux in relay 31, sufficient to cause it to attract its armature *a*, the result of which will be explained later on.

A change in the wave length may be produced by shunting an additional condenser 100 53 across the plate coil 47, the circuit consisting of the wire 54 connecting to the wire 48, the armature *a* of relay 55, wire 56, condenser 53 and wire 57 connecting to the wire 46. This additional circuit is closed and the 105 condenser is operative when the green signal lamp at the exit end of the block receives current, at which time current flows from the battery and wire 17 over armature 14^a, wire 60, armature 14^c, wire 61, relay 55 and wire 62 to return wire 20. This circuit is opened at 14^a when the first block in advance is occupied and at 14^c, when the second block in 110 advance is occupied, so that the relay 55 is energized only when the green signal lamp 115 indicates clear track for at least two blocks in advance.

A fifth relay 70 is so constructed that it gains and loses its energy very slowly. Its function is to close the circuit to the relay 14 of the next station in the rear whenever the rails of the block to which its own station is connected, are unoccupied, and the delayed loss of energy permits either of the circuits which conduct current to this relay 70 to be substituted for the other.

This relay receives current when the block to which it is connected is unoccupied. One end of its winding always connects directly to the battery by means of wire 26. The 120

other end connects to the armatures 70^a and 31^a by means of the wire 71. The relay 31 is energized each time the block is occupied under which condition the circuit to this 5 relay 70 is closed over the wire 71, armature 31^a, wires 72, 29, 20, armature 7^a and wire 21 to the battery. The armatures 70^a and 70^b are thereupon attracted and the parts remain in this position until the train leaves that 10 block. At this instant the relay 31 becomes de-energized but the relay 7 becomes energized. Current now flows from relay 70 over wire 71, armature 70^a, wire 73, armature 7^a and wire 21 to the battery as indicated in station C. The parts remain in this condition 15 until a train enters the block, as indicated in station D, when the circuit to the relay 70 is again closed by the armature 31^a.

The wire 16^b is always connected to either 20 one or the other end of battery 13^b through armature *c* of relay 14^b. Wire 15^b connects to armature *b* of relay 70^b and therefore receives current when this relay is energized and block B is unoccupied. When block B 25 is occupied, relay 7^b is de-energized and the circuit over its armature *a* is open. If now the circuit over armature *a* of relay 31^b is also open by failure of current from the transformer of station B, no circuit to relay 30 70^b will be closed until the transformer is again operative. Failure of the transformer at any station therefore causes a "danger" indication at the next station in the rear. If any block is occupied, the train control 35 instrumentalities of the next two blocks in the rear will be ready to propagate "danger" currents in the rails of the blocks to which they are connected as soon as a vehicle enters the sections which are charged thereby.

40 A locomotive equipment is shown in Fig. 3 and comprises the two collector coils or loops 100 and 101 connected to the thermal-junctions or thermo-couples 102 and 103 respectively and having the adjustable condensers 104 and 105 in their circuits so that each of these circuits may be tuned for proper wave length to receive one of the induced currents which travel along in front of the leading axle of the locomotive as it runs along 45 a track section in which high-frequency current is propagated as before described. The thermal-junctions convert or translate the picked up oscillating currents into direct currents and the two direct currents travel in 50 opposite directions over the wires 106 and 107 to the polar relay 108 whose armature *a* swings clockwise when current is received by a collector coil from a block at whose exit end a green light is visible and counterclockwise 55 when a red or yellow light is visible under these conditions. That is, the relay armature swings to the position shown in Fig. 1 under "danger" conditions and to the position shown in Fig. 3 under "clear" conditions. 60 These collector coils are preferably mounted

on the pilot frame of the locomotive just ahead of the lead wheels and spaced a short distance from the rails.

Assuming that the "clear" current has been picked up by coil 100 and that it caused the 70 armature of relay to swing to the position shown in Fig. 3, current from the battery 110 flows over wires 112 and 113, armature *a* of brake control relay 114, resistance 115, brake control relay 114, resistance 116 and 75 wire 117 to the battery. This circuit is normally closed. Current also passes from wire 112 over armature *b* of signal relay 118, wire 119, green lamp 120 and wires 121, 122 and 117 to the battery. Current also passes from 80 wire 112 over armature 118^a, wire 124, relay 118, resistance 125, resistance 116 and wire 117 to the battery. We therefore have relays 114 and 118 energized over stick circuits which remain closed until a current is picked 85 up by coil 101. The resistances 115, 116 and 125 may be equal, and may be equal the resistance of relay 114.

When the parts are as shown in Fig. 3 and current is picked up by coil 101 to cause the 90 armature 108^a to swing to the position shown in Fig. 1, the current from the battery will take a new path of less resistance over wires 112 and 127, armature 108^a, wire 128 and resistance 125, resistance 116 and wire 117, 95 short circuiting the relays 114 and 118, which, when de-energized, drop their armatures. Current now flows from wire 112 over armature 118^b and wire 128 to the red lamp 129 and over wires 121 and 122 to the battery. 100 The red light will now signal "danger" conditions, that is, indicate to the engineer that the block in advance is occupied. The same signal is given whenever the track way installation at the exit end of the next block in 105 advance fails to operate.

Two forestalling keys 131 and 132 are located at different points, preferably at the engineer's and at the fireman's stations, and when both are depressed, current will flow 110 from wire 112 by way of wire 134, key 132, wire 135, key 131, wire 136 to relay 114 and resistance 116 and wire 117 to the battery. As the resistance of relay 114 is the same as that of resistance 125, sufficient current 115 passes over this last described circuit to energize relay 114. The keys must be kept depressed until the locomotive has left that portion of the track which carries the current which caused armature 108^a to swing to the 120 right, whereupon this armature will swing to the dotted line position shown in Fig. 3. Current still flows to red lamp 129 and does so until lamp relay 118 is again energized, but current flows from the battery over wires 112 and 113, armature 118^a, resistance 115, relay 114, resistance 116 and wire 117 to the battery, keeping relay 114 energized and permitting the forestalling keys to be released. 125

130 As soon as the collector coil 100 picks up a

proper current and armature 108^a swings to the position shown in Fig. 3, current passes to relay 118 over wires 112 and 127, armature 108^a and wire 124. As soon as the relay 5 118 lifts its armatures, the current follows the shorter path from wire 112 over armature 118^a and wire 124, which path it may continue to follow even after armature 108^a swings to neutral position.

10 When relay 114 is energized, current also flows from wire 112 over armature 114^b and wire 141 to the solenoid 142 of an electro-pneumatic valve 144 and holds the valve 145 on its seat, the current returning over wires 15 146, 122 and 117. When the relay 114 and solenoid 142 are de-energized, the train pipe pressure is reduced so that the brakes will be applied.

The pipe 147 leads to the electro-pneumatic 20 valve 144 from a main reservoir, and when the valve 145 drops, this air flows through the valve body 144, pipe 148, check valve body 149, and pipes 150 and 151 to the cylinders 153 and 154 respectively. When air flows to 25 the cylinder 153, the piston 155 is forced inward to press the valve 156 into its seat, thus preventing air from flowing from the engineer's train valve 157 to the train pipe 158. The engineer may, however, permit air to 30 flow from this pipe 158 to reduce the pressure therein, the check valve 159 permitting such operation.

As the air flows to the cylinder 154, the piston 161 forces the disk-valve 162 inward from 35 its outer seat onto its inner seat. When in its outer position, equal air pressure exists within the pipe 163 and reservoir 164, and above and below the piston 165 which connects to a valve 166. When the valve 162 is in its inner 40 position, the pipe 163 and the space below the piston 165 are cut off from the space above the piston and from the reservoir 164, and the air above the piston is permitted to escape through the passage 167 and vent 168. Passage 45 167 is regulated by valve 169.

When the pressure above the piston 165 is reduced, the pressure below the piston raises it and permits train line air from the pipe 163 to escape through the vent 170, and this reduction in train pipe pressure causes the brakes 50 to be applied. As the air above the piston would escape too rapidly unless the passage 167 were made very small, the auxiliary reservoir 164 is provided so that the air therein 55 will cause the pressure above the piston 165 to reduce very slowly.

As stated before, the red lamp 129 receives current as soon as the locomotive reaches that portion of the track in which "danger" current 60 is propagated, and the engineer and fireman have ample time to depress the forestalling keys before the air from pipe 147 accumulates back of piston 155—161 sufficiently to cause the brakes to be applied. But should 65 either engineer or fireman be incapacitated

and fail to depress his forestalling key, the brakes will be applied and the train stopped. When the circuit to the electro-pneumatic valve is closed, the engineer can again bring the train pipe pressure to normal by proper manipulation of his valve 157. Any pressure 70 which may have accumulated in the cylinders 153 may slowly escape through the small vent 174, the valve 175 being formed to permit a slight leakage.

75 We claim:—

1. In a train control apparatus, an installation adapted to be mounted on a vehicle equipped with air brakes to co-operate with instrumentalities placed at intervals along the track and adapted to propagate high-frequency currents of different wave lengths in the rails, which wave lengths depend upon the occupancy of the track, said vehicle installation comprising a plurality of current collecting devices adjacent to but spaced from the rails of the track and an electric circuit connecting to said devices, means for changing the high-frequency currents into direct currents moving in opposite directions in said 85 circuit, a polar relay in said circuit adapted to be energized by said direct currents and having an armature; a current source, an electro-pneumatic valve controlling the operation of the air brakes of said vehicle, and a 90 circuit between said current source and said electro-pneumatic valve controlled by the armature of said polar relay.

2. In a train control apparatus, an installation adapted to be mounted on a vehicle 100 equipped with air brakes to co-operate with instrumentalities placed at intervals along the track and adapted to propagate high-frequency currents of different wave lengths in the rails, which wave lengths depend upon the occupancy of the track, said vehicle installation comprising a plurality of current collecting devices adjacent to but spaced from the rails of the track and an electric circuit connecting to said devices, means for changing the high-frequency currents into direct currents moving in opposite directions in said 105 circuit, a polar relay in said circuit adapted to be energized by said direct currents and having an armature; a current source; an electro-pneumatic valve controlling the operation of the air brakes of said vehicle, and a 110 circuit between said current source and said electro-pneumatic valve controlled by the armature of said polar relay, a second relay to 115 open and close said last named circuit, manually operable means on the vehicle and an independent circuit between said second relay and the current source.

3. In a train control apparatus, an installation adapted to be mounted on a vehicle 120 equipped with air brakes to co-operate with instrumentalities placed at intervals along the track and adapted to propagate high-frequency currents of different wave lengths in 125 130

- the rails, which wave lengths depend upon the occupancy of the track, said vehicle installation comprising a plurality of current collecting devices adjacent to but spaced from the rails of the track and an electric circuit connecting to said devices, means for changing the high-frequency currents into direct currents moving in opposite directions in said circuit, a polar relay in said circuit adapted to be energized by said direct currents and having an armature; a current source, an electro-pneumatic valve controlling the operation of the air brakes of said vehicle, and a circuit between said current source and said electro-pneumatic valve controlled by the armature of said polar relay, a relay controlling the circuit between said current source and said electro-pneumatic valve, a circuit between said current source and said relay adapted to be shunted by the circuit to the armature of said polar relay, a second circuit between said current source and said controlling relay, and manually operable means for closing said circuit when the controlling relay becomes deenergized.
4. In a train control apparatus of the class described in claim 1, thermal couples for changing the high-frequency oscillating current into direct current.
5. In a railway vehicle installation of a train control system, a current source, an electro-pneumatic valve, a control relay, a circuit between the current source and valve, embodying an armature of said relay, a circuit between said current source and said armature embodying another armature of said relay, means to pick up high-frequency current from adjacent the tracks on which the vehicle is moving, a relay influenced by said current, and a circuit embodying the armature of said last named relay to shunt the current from said source around the control relay to cause it to become de-energized and the circuits embodying its armatures to be opened.
6. In a railway vehicle installation of a train control system, a current source, an electro-pneumatic valve, a control relay, a circuit between the current source and valve, embodying an armature of said relay, a circuit between said current source and said armature embodying another armature of said relay, means to pick up high-frequency current from adjacent the tracks on which the vehicle is moving, a relay influenced by said
- current, and a circuit embodying the armature of said last named relay to shunt the current from said source around the control relay to cause it to become de-energized and the circuits embodying its armatures to be opened, and manually operable means to cause the control relay to be re-energized to close the circuits which embody its armatures.
7. In a railway vehicle installation of a train control system, the combination of a normally closed electro-pneumatic valve, and a brake system adapted to operate when said valve is open, a control relay for said valve, a current source, a circuit between the current source and the valve embodying an armature of said control relay which circuit is held normally closed by said relay, a pair of collector coils adapted to pick up control currents from the track rails, means operated by the picked up currents embodying a polar relay and its armature, a pair of signal lamps and a relay to control the current thereto, circuits between the current source and said lamps embodying the armatures of said last named relay, and circuits between said current source and the lamp control relay and the valve control relay and embodying the armature of the polar relay whereby the current from said source may be shunted around said control relays.
8. In a train control apparatus, an installation adapted to be mounted on a vehicle equipped with air brakes to co-operate with instrumentalities placed at intervals along the track and adapted to propagate high-frequency currents of different wave lengths in the rails, which wave lengths depend upon the occupancy of the track, said vehicle installation comprising current collecting means adjacent to but spaced from the rails of the track and an electric circuit connecting to said means, means for changing the high-frequency currents into direct currents in said circuit, responsive means in said circuit adapted to be energized by said direct currents and having movable mechanism; a current source, an electro-pneumatic valve controlling the operation of the air brakes of said vehicle, and a circuit between said current source and said electro-pneumatic valve controlled by said movable mechanism.
